THERMOSTATIC FUEL CONTROL FOR
HEATERS

Harry C. Little, San Rafael, Calif.

Application April 2, 1940, Serial No. 327,454

2 Claims. (Cl. 126—116)

The invention relates to air circulating heaters and more particularly to a thermostatic fuel control for such heaters.

An object of the present invention is to provide a thermostatic control of the character described which will operate as a safety device in an air circulating heater to limit the maximum temperature and which is responsive to the temperature in the warm air passage of the heater and may be incorporated into the heater as a unitary part thereof.

Another object of the invention is to provide a thermostatically controlled safety device of the character described which will be simple and positive and fool proof in its operation and which will be constructed of a minimum number of simply formed rugged and inexpensive parts.

A further object of the invention is to provide a control of the character above which will subject the thermostatic element to a minimum stress when heated and which will provide for the closing off of the fuel supply to the burner should the thermostatic element become broken.

Yet another object of the invention is to provide a thermostatic control of the character described which may be readily dismantled for inspection, cleaning, repair or replacement of any of the operating parts of the control.

Still a further object of the invention is to provide a control of the character described which may be particularly designed for use in the oil line of an oil burner and which will have the final control of the oil flow to the burner and which may nevertheless be used in conjunction with and without interfering with the operation of an automatic float control oil valve in the oil flow line to the burner.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a vertical sectional view of an air circulating floor furnace embodying the control of the present invention, the latter being shown in elevation.

Figure 2 is a vertical sectional view of the control means of the present invention, the bottom

portion of the view being turned 90° from the top part of the view.

Figure 3 is a plan view of the control means illustrated in Figure 2.

Figure 4 is a vertical sectional view of a portion of the upper end of the control means taken substantially at right angles to the plane of line 4—4 of Figure 3.

The thermostatic fuel control of the present invention is particularly adapted for use with an air circulating heater such as for example, the floor furnace illustrated in the accompanying drawing. In this type of heater there is provided a vertical warm air passage extending alongside of the combustion casing of the heater and which is vented into the room or other space to be heated. The combustion casing is customarily provided with a burner at its lower end for heating the casing and a fuel conduit leading to the burner. In accordance with the present invention a valve means is provided in this conduit and a thermostat means is mounted in the warm air passage and is operatively connected to the valve and is so designed as to be responsive to an abnormally high operating temperature in said passage to close the valve. Under ordinary circumstances of operation with the air passages of the heater unobstructed, and with the burner receiving not more than its rated amount of fuel, the thermostat means will remain substantially inoperative. Danger however exists should the air passages of the heater become partially or fully obstructed or if the burner is supplied too much fuel. In the case of a floor furnace it frequently happens that a rug or other object is placed over the air discharge passage into the room in such a manner as to partially or fully obstruct the air flow and in the case of the ordinary space heater it is not infrequent that a garment or other object is placed on the heater for warming or drying. In either of these instances the air is confined in the passages of the heater and a dangerous rise in temperature of the heater is likely to take place. Even where the air passages are not obstructed a dangerous overloading of the unit may occur by reason of an abnormally great flow of fuel to the burner, as may be caused by a failure of the fuel meter valve usually used in the line or by reason of causes external to the heater itself. In any of these cases the thermostatic control of the present invention operates to reduce, or entirely close off the flow of fuel to the burner until the cause of the overloading is removed.

With reference more specifically to the accompanying drawing, the thermostatic control has

been illustrated in conjunction with a floor furnace 11 of more or less standard design including a combustion casing 12, an outer casing 13 and intermediately positioned walls 14 which divide the space between the combustion casing 12 and the outer casing 13 into vertical air passages 16 and 17 adapted to convey the air into and out of the heater. A top grill 18 is mounted across the upper end of the casing 13 so as to permit entry and discharge of air into and from passages 16 and 17. As here shown, the wall 14 extends downwardly from an intermediate portion of the grill 18 to adjacent the lower end of the heater casing 12 and cool air is drawn downwardly into the passage 16 defined between the wall 14 and the casing 13 to displace air which is heated and which rises in the passage 17 located between wall 14 and the heater casing 12. The passage 17 extends upwardly alongside of the heater casing and registers with the mid portion of the grill 18. In the case of a floor furnace as is here shown, the outer casing 13 is set in an opening formed in the floor 19 of a room so that the several parts above described depend from the floor level. A fuel burner 21 is mounted at the bottom of the casing 12 and discharges its products of combustion into the casing for heating the latter, and a flue 22 is here connected adjacent the bottom of the casing 12 for discharging the spent products into a stack. Fuel is conducted to the burner from a metering valve 23 by way of connected conduits 24 and 26 and is conducted to the metering valve 23 from a source by way of a conduit 27.

As above described, a fuel regulating valve 28 is mounted in the fuel passage leading to the burner and a thermostatic means 29 is mounted in the warm air passage 17 and the same is operatively connected to the valve and is responsive to increasing temperatures in the passage to throttle down the valve 28. In the present instance the valve 28 is contained within a valve body 31 connected to the conduits 24 and 26. A valve seat 32 is provided in the form of a removable plug threaded into the lower end of the body 31 and the valve 28 is a needle type valve which moves downwardly into an opening 33 provided in the member 32 for sealing off the fuel flow. A tube 34 is threaded into the upper end 36 of the valve body and extends vertically therefrom into the air passage 17 and is arranged in longitudinal alignment with the movement of the valve 28. A bracket 37 is secured to the upper end 38 of the tube and is in turn provided with a skirt portion 39 adapted for connection to the side wall 14 of the heater. Preferably, the tube 34 is of a length sufficient to extend from adjacent the bottom of the burner to adjacent the top of the passage 17. A valve stem or rod 41 is secured to or formed integrally with the valve 28 and extends upwardly through the interior of the tube and out of the upper end of the tube, whereby the upper end 42 of the stem projects upwardly from the upper end 38 of the tube within the confines of the bracket 37. The bracket in its present form is of generally U-shaped construction secured adjacent its center to the upper end 38 of the tube as by means of nuts 43 and 44 and includes a pair of transversely spaced sides 46 and 47. The thermostatic element of the preferred form of the invention consists of an elongated strip 48 of bi-metal which is here supported in the bracket by extension of opposite ends 49 and 51 of the strip through slots 52 and 53 in the sides 46 and 47 of the bracket. Preferably,

some means such as the cotter keys 54 and 56 here shown, are provided for preventing a transverse movement of the strip relative to the bracket out of a supported position.

As will be best seen in Figures 2, 3 and 4, the strip 48 is mounted across the longitudinal axis of the rod in offset relation thereto and is here connected to the rod by means of a yoke 57 embracing the strip and extending laterally across the axis of the rod 41 and formed with threaded openings 58 and 59 secured on the threaded upper end 42 of the rod. A cap nut 61 is preferably provided over the upper end of the rod. In accordance with the present arrangement, the strip 48 in cool condition extends substantially straight across the bracket and the length of the stem 41 is such that in the cool position of the strip, the rod and valve is supported in an elevated open position of the valve, as illustrated in Figure 2. The bi-metal characteristics of this strip are such that upon being heated the strip will bow downwardly so as to permit a gravitation and lowering of the rod and stem towards a seated position of the valve and at an abnormally high temperature the valve will be fully closed. By reason of the vertical positioning and alignment of the several parts, the valve and rod will normally tend to gravitate to a closed position of the valve and hence the thermostatic strip is not called upon for any substantial actuating force when heated to close the valve. Also, should the strip fail in its operation as by reason of breakage or failure to return to a straight position after being overheated, the valve will close and remain closed until the defect is corrected.

It will be clear that one of the functions of the tube 34 is to act as a vertical guide for the valve stem and in addition, where oil fuel is used, the upper end of the tube is left open to the atmosphere so as to provide a vent for any oil vapor formed in the oil line at or adjacent to the valve body 31.

The apparatus depicted in the accompanying drawing has been particularly designed for use with a burner using oil as its fuel. In such case it is preferable that the metering valve 23 be one that is float controlled, that is a valve which is constantly filled to a predetermined level with oil by means of a float controlled valve. In such a case it is desirable as here shown, to locate the safety valve 28 in the line between the float control valve 23 and the oil burner 21, so that upon closing of the safety valve 28, a minimum amount of oil will be available for flowing to the oil burner.

One of the advantages of the construction illustrated in the preferred form of the invention, is that the fuel flow is gradually throttled down with increasing temperatures so as to maintain the operation of the heater at a safe temperature. The location of the safety valve between the float control valve 23 and the oil burner gives the safety valve 28 the last and final control of the oil input into the burner, and regardless of the setting of the rate of flow of oil cut off the float valve 23, the oil flow can be reduced or entirely shut off by the safety valve 28.

In accordance with the present invention it is extremely desirable that the thermostatic element be responsive to the temperature of the air in the hot air discharge passage of the heater and so near as possible be responsive only to the temperature of such air and not to the temperature of the heated walls of the heater. I have

found that the most effective control is obtained by depending upon the increasing temperature of the air in the hot air discharge passage rather than the increasing temperature of any of the metal parts of the heater. For this reason I prefer to mount the thermostatic element 29 adjacent the top of the hot air discharge passage in furtherest removed position from the heater casing 12 so that the heat received by the thermostatic element by radiation from the heater casing 12, will be reduced to a minimum. Thus the mounting of the thermostatic element directly in the air passage and more particularly at the upper discharge end of the air passage forms an important feature of the present invention.

As will be understood, other forms of thermostatic devices different from the specific bi-metal strip herein illustrated, may be used.

I claim:

1. In combination with a floor furnace, an air circulating heater including a combustion casing and exteriorly spaced walls defining a vertical warm air passage alongside of said casing and a fluid fuel burner mounted at the bottom of said casing to heat the same and having a fuel inlet conduit underlying said passage, a thermostatically operated valve unit comprising a valve body adapted for connection to said conduit at a position under said passage, a valve mounted for vertical reciprocation in said body and closing the passage through said body in its lower position, a tube connected to said valve body and extending upwardly therefrom in alignment with the movement of said valve, a valve stem ex-

- tending vertically through said tube, a bimetal strip supported by the upper end of said tube and connected to said stem for normally supporting the latter in an elevated open position of said valve and being responsive to increasing temperature in said passage to permit a gravitation of said stem and valve towards closed position of said valve, said tube being open at its upper end to permit discharge of oil vapor.
- 5 2. In combination with a floor furnace, an air circulating heater including a combustion casing and exteriorly spaced walls defining a vertical warm air passage alongside and above said casing and communicating with a delivery opening at the top of the heater, said heater also having a fuel burner and a fuel inlet conduit located at the bottom of the casing, a valve comprising a body operatively connected to said conduit and positioned adjacent said burner, a tube connected 10 to and extending upwardly from said body to adjacent said delivery opening and being open to permit discharge of oil vapor therefrom, a valve member mounted in said tube and body for closing the passage through the valve body, a thermostat at the upper end of said heater passage positioned in the normal and direct vertical path of the heated air discharging through such passage to said delivery opening, and means connecting said valve member and thermostat so that 15 said valve member will move to close said valve passage in response to an increase in temperature in said heater passage.
- 15 3. In combination with a floor furnace, an air circulating heater including a combustion casing and exteriorly spaced walls defining a vertical warm air passage alongside and above said casing and communicating with a delivery opening at the top of the heater, said heater also having a fuel burner and a fuel inlet conduit located at the bottom of the casing, a valve comprising a body operatively connected to said conduit and positioned adjacent said burner, a tube connected 20 to and extending upwardly from said body to adjacent said delivery opening and being open to permit discharge of oil vapor therefrom, a valve member mounted in said tube and body for closing the passage through the valve body, a thermostat at the upper end of said heater passage positioned in the normal and direct vertical path of the heated air discharging through such passage to said delivery opening, and means connecting said valve member and thermostat so that 25 said valve member will move to close said valve passage in response to an increase in temperature in said heater passage.
- 25 4. In combination with a floor furnace, an air circulating heater including a combustion casing and exteriorly spaced walls defining a vertical warm air passage alongside and above said casing and communicating with a delivery opening at the top of the heater, said heater also having a fuel burner and a fuel inlet conduit located at the bottom of the casing, a valve comprising a body operatively connected to said conduit and positioned adjacent said burner, a tube connected 30 to and extending upwardly from said body to adjacent said delivery opening and being open to permit discharge of oil vapor therefrom, a valve member mounted in said tube and body for closing the passage through the valve body, a thermostat at the upper end of said heater passage positioned in the normal and direct vertical path of the heated air discharging through such passage to said delivery opening, and means connecting said valve member and thermostat so that said valve member will move to close said valve passage in response to an increase in temperature in said heater passage.

HARRY C. LITTLE.
